hold Utilities Corporation, Chicago, Ill., a cor-
poration of Illinois

Application February 25, 1932, Serial No. 594,980

13 Claims. (Cl. 68—9)

This invention relates to improvements in ironing machines and its purpose is to provide improved mechanism for supporting and effecting relative movement of two ironing elements such as a rotatable roll and a relatively movable heated shoe. The principal object of the invention is to provide a simplified device comprising means for supporting the shoe in a novel manner and for actuating the shoe to move it toward and from the roll. A further object of the invention is to provide an ironing machine in which the shoe has movements substantially in a horizontal plane toward and from the roll, as distinguished from a rocking or tilting movement about a horizontal axis which has characterized certain ironing machines heretofore in use. Still another object of the invention is to provide an ironing machine comprising a shoe which is carried by an operating lever having actuating mechanism by which it is swung about its pivotal point to move the shoe toward or from the roll. A further object of the invention is to provide an ironing machine comprising a movable shoe carried by a lever which is actuated by power driven mechanism capable of being manually controlled to cause the shoe to be held in position to engage the clothes being ironed against the roll or in a retracted position spaced from the roll. A further object of the invention is to provide an ironing machine comprising a rotatable roll and a relatively movable shoe in combination with actuating mechanism which is contained within a housing adapted to serve as a support for the roll and shoe and which is so disposed that the housing has relatively small vertical dimensions to permit the mounting thereof upon a supporting table over which the roll and shoe extend. Other objects relate to various features of construction and arrangement which will appear more fully 40 hereinafter.

The nature of the invention will be understood from the following specification taken with the accompanying drawings, in which one embodiment is illustrated. In the drawings,

45 Fig. 1 shows a rear elevation of an ironing machine embodying the present invention with the supporting legs of the table broken away;

Fig. 2 shows a top plan view of the ironing machine illustrated in Fig. 1 with portions thereof broken away, and illustrating by dotted lines the retracted position of the shoe;

50 Fig. 3 shows an enlarged vertical section through the housing, portions of the actuating mechanism contained therein with portions of the roll and shoe illustrated in rear elevation;

Fig. 4 shows a vertical section taken on the line 4—4 of Fig. 3;

Fig. 5 shows a horizontal section taken on the line 5—5 of Fig. 4; and

Fig. 6 shows a detail vertical section taken on the line 6—6 of Fig. 5.

As illustrated in the drawings, the invention comprises a table 10 supported upon legs 11 and having secured to one end portion thereof a housing 12 provided with flanges 12^a which rest upon the table and are engaged by connecting bolts 13 passing through the table top. The housing 12 carries a rotatable ironing roll 14 and a relatively movable shoe 15, which are actuated in the manner hereinafter described by mechanism contained within the housing. The housing is provided on its vertical end face with an opening which is normally closed by a cover plate 16 having the lower portion thereof formed integrally with the casing 17 of an electric motor by which the mechanism is driven. This cover plate 16 has secured thereto, within the housing 12, a frame 18, the body portion of which is spaced from the inner portion of the cover plate by bosses 18^a which are engaged by studs 19 having threaded 70 engagement with recesses 20 formed in the cover plate. The driving mechanism is carried by the cover plate 16 and frame 18 so that all of these parts may be detached as a unit from the housing 12 upon removal of the studs 21 which pass through the outer annular flange of the cover plate and engage the inner marginal flange 12^b of the housing. A gasket 22 is interposed between these flanges of the cover plate and housing in order to provide an oil-tight connection, thus permitting lubricating oil to be contained within 75 the housing for lubricating the various parts of the actuating mechanism.

The casing 17 of the electric motor is provided with a field winding 24 and an armature 25 which is rotatable within the field winding on the motor shaft 26. This shaft is journaled at its ends in bearings carried by the motor casing 17, the bearing at the inner end of the casing being formed in the end wall 17^a of the motor casing which is provided with a hub 27 having secured therein a bushing 28 in which the shaft 26 is journaled. This shaft 26 has a pinion 29 secured to the inner end thereof to mesh with a relatively large gear 30 which is located upwardly therefrom. This gear 30 is secured upon a countershaft 31 which is journaled in bearings 32 and 33 carried by the motor casing and the frame 18, respectively. A pinion 34 is secured on the shaft 31 adjacent the bearing 32 and this pinion meshes with a 80 100 105 110

relatively large gear 35 which is adapted to revolve upon another shaft 36 which has its outer end journaled in a bearing hub 37 formed integrally with and projecting inwardly from the cover plate 16, while the inner end thereof is journaled in a bearing hub 38 which is formed integrally with the frame 18. The gear 35 serves as a driving gear for effecting the rotation of the roll and also for actuating the shoe. 5

10. The connections from the gear 35 to the roll 14 are made through a relatively large pinion 40 which is formed integrally therewith or secured thereto, so that it revolves upon the shaft 36. This pinion 40 meshes with a gear 41, shown particularly in Fig. 5, which is fixed upon the end of a roll driving shaft 42. This shaft is journaled in a bearing 43 which is formed integrally with the frame 18 and it is journaled at its inner end in a bushing 44 which is mounted in an aperture formed within a bearing block 45 formed integrally with the inner wall of the housing 12. This bearing block has secured therein a stationary hollow axle 46 adapted to support the roll 14 which comprises a cylindrical metal shell 48 secured at its ends to radially extending disks 49, the inner one of which is shown in Fig. 5. The inner disk 49 is secured through a ring 50 and studs 51 to an annular gear 52 which is mounted to revolve upon a bushing 52^a secured to the axle 46 adjacent the bearing block 45. This gear 52 meshes with a pinion 53 secured to or formed integrally with the inner end of the roll driving shaft 42 so that when the train of mechanism from the driving motor to the shaft 42 is in operation, the roll 14 is rotated. The metallic shell 48 of the roll is covered on its outer side by a winding 55 of suitable fabric adapted to contact directly with the clothes to be ironed. A disk 56 is secured to the outer end of the axle 46 and provision is made at this outer end for preventing endwise movement of the roll on its bearings. 30

35. The shoe 15 has a concave inner face which is adapted to conform to the curvature of the external surface of the roll 14 when the shoe is in contact with the clothes being ironed and between this inner metal face 15^a of the shoe and the rear wall 15^b thereof, there are located the usual electric heating elements, adapted to be connected to a source of current supply, by which the shoe is heated during the ironing operation. This shoe 15 is supported by means of a lever 60 having a part 60^a which is flattened in a horizontal plane to fit between two horizontal bearing hubs 61^a which are formed as a part of a bearing bracket 61 secured to the casing 12 by studs 62, as shown particularly in Figs. 1 and 2. The lever 60 is pivotally connected to the hub 61^a by a vertical pin 63 which is secured at its lower end by a nut 64. The part 60^a of this lever is flattened in a vertical plane at its outer end and is welded or otherwise secured to the part 60^b of the lever which is in the form of a flat leaf spring occupying a vertical plane. At its outer end, this spring portion 60^b of the lever is secured to a casting 60^c which terminates in a hub portion adapted to be received between two ears 65^a which project outwardly in horizontal planes from a bracket 65 which is secured in a central position, horizontally and vertically, to the rear side of the shoe 15. The shoe is thus supported by the lever 60 and may be moved toward and from the roll by swinging the lever horizontally about the pivot pin 63. Due to the pivotal connection of the shoe with the outer end of the lever 60, the shoe is adapted to adjust itself to

45. 50. 55. 60. 65. 70. 75. 80. 85. 90. 95. 100. 105. 110. 115. 120. 125. 130. 135. 140. 145. 150.

the position of the roll and the clothes thereon when engagement occurs.

The movement of the shoe 15 toward and from the roll 14 is effected by an eccentric disk 66 which is secured on the shaft 36 adjacent to the gear 35. This eccentric is surrounded by an eccentric strap 67, shown particularly in Figs. 5 and 6, which has an arm 67^a formed integrally therewith and which is capable of being tightened to grip the eccentric with the desired degree of friction, by means of a stud 68 having a coil spring 69 interposed between the head of the stud and the adjacent ear of the strap. The arm 67^a of this eccentric strap is provided at its end with a pair of flanges 70 between which there is fitted a stem 71 having a spherical ball 72 formed on the outer end thereof. A pivotal connection is established between the arm 67^a and the stem 71 by a headed pin 73 which passes through these members and is engaged at its other end by a washer 74 and a cotter pin 75. The ball 72 engages a spherical socket 76 which is formed partly in the head 60^d of the lever 60 and partly in the retaining plate 77 which is secured to the part 60^d by means of studs 78. The retaining plate 77 has an enlarged opening 77^a to accommodate the movement of the stem 70 when it oscillates about the pivot pin 73 in response to the movement of the ball and socket connection between the stem and the shoe operating lever. It will be apparent that when the shaft 36 is rotated, the corresponding rotation of the eccentric 66 will move the lever 60 through the connections just described so that the shoe 15 will be moved toward or from the roll.

The shaft 36 is adapted to be rotated to effect the movement of the shoe through connections which are detachably made between the shaft and the previously described pinion 40 which rotates at all times when the driving motor is in operation. For this purpose, the pinion 40 is provided on its lateral face with a series of clutch teeth 40^a which are adapted to interlock with similar clutch teeth 80^a formed on a clutch member 80 which is splined upon the enlarged part 36^a of the shaft, this part being provided with longitudinal teeth which are engaged by inwardly extending projections of the clutch member to form a driving connection between the clutch member and the shaft while permitting axial movement of the clutch member to bring the clutch teeth 80^a into engagement with the clutch teeth 40^a. In addition to its bearing directly on the shaft 36, the clutch member 80 is provided with a tubular extension 80^b which is slidably mounted upon the hub member 37 previously described. A coil spring 81 is mounted on this extension 80^b between an annular shoulder on the clutch member and the inner surface of the cover plate 16 so that the spring normally tends to move the two sets of clutch teeth into engagement with each other. The clutch member is provided with two diametrically opposed recesses 80^c either of which is adapted to be engaged by the extremity 82^a of a shifter bar 82 which is pivotally connected at its other end through a pin 83 with a crank arm 84 secured on a shaft 85 by means of a set screw 86. The shaft 85 is journaled in an enlarged bearing hub 88 which extends inwardly from the inner side of the cover plate 16 and the other end of this shaft is enlarged as shown at 85^a and journaled in another bearing hub 89 carried by the plate 18. The projecting end of the shaft 85 has a crank handle 90 secured thereon for engagement by the hand of the operator in controlling the actuation of the clutch mem-

ber 80. The shifter bar 82 slides between a plate 91 which forms a part of the frame 18 and another small plate 92 which is spaced outwardly from the plate 91 and secured thereto by screws 93. The plate 92 has a slot 92^a therein which is engaged by a pin 94 secured to the face of the shifter bar 82. A coil spring 95 is connected between one of the screws 93 and the pivot pin 83 of the crank arm 84 so that this spring normally tends to maintain the shifter bar in engagement with the clutch member and to cause the end 82^a of the shifter bar to engage one of the recesses 80^c when that recess is in the proper position. A flat leaf spring 97 is secured to the inner side of the shifter bar 82 and bears against the plate 91 so that it maintains the end 82^a of the shifter bar in engagement with the cam surface 98 formed on the face of the groove of the clutch member in which the end of the shifter bar is located. The configuration of the annular cam face 98 is such that when the shifter bar 82 is in position to engage either of the recesses 80^c of the clutch member, the clutch member is withdrawn to disengage its teeth 80^a from the teeth 40^a of the driving pinion, and the shifter bar may be engaged with a recess 80^c to hold the shaft 36 and eccentric 66 against rotation. When the shifter bar is withdrawn from either recess 80^c, the adjacent projection 98^a of the cam face slips out of engagement with the shifter bar and the clutch member 80 is moved inwardly under the influence of the spring 81 to bring the teeth 40^a and 80^a into engagement with each other. This then results in the rotation of the shaft 36 which is driven from the pinion 40 through the clutch member and, as a result, the eccentric 66 is rotated and the lever 60 is turned about its pivot to move the shoe 15 in one direction, toward or from the roll 14. Assuming that it is moved toward the roll, the motion continues until the shoe reaches the proper ironing position with respect to the roll, when the clutch teeth 40^a and 80^a are automatically disengaged by the coaction of the end of the shifter bar with the cam surface 98, whereupon the spring 95 forces the end 82^a of the shifter bar into engagement with one of the recesses 80^c to hold the clutch member, shaft and eccentric in that position so that the shoe is prevented from moving away from the roll during the ironing operation. When the operator wishes to move the shoe away from the roll, the handle 90 is turned to withdraw the shifter bar 82 from the recess 80^c, whereupon the clutch member 80 is moved by the spring 81 into engagement with the clutch teeth of the pinion 40, so that the shaft 36 then makes another half revolution during which the eccentric 66 is rotated to move the shoe away from the roll. At the end of this half revolution, the clutch teeth are again disengaged by the coaction of the cam surface 98 with the end of the shifter bar and then the spring 95 again operates to move the shifter bar into engagement with the other recess 80^c so that the shoe 15 is held in a position spaced from the roll. It will be apparent from the foregoing description that when the shoe has been moved into contact with the roll and also when the shoe has been moved outwardly to its extreme position spaced from the roll, the shifter bar 82 automatically engages one of the recesses 80^c to hold the clutch member 80 against rotation, thereby holding the gear 40 and the eccentric 66 against rotation.

with the ironing shoe 15 in either of these extreme positions.

It will be apparent that the construction described above is one which permits a ready and convenient operation of the shoe and roll by the driving mechanism and that the construction and arrangement of this mechanism is such that it occupies a relatively small space and has a relatively small vertical dimension so that it may be contained within a housing of such size that it is adapted to be mounted directly upon the top of the table 10 which thus serves as a support for the clothes being ironed.

Although one form of the invention has been shown and described by way of illustration, it will be understood that it may be constructed in various other forms coming within the scope of the appended claims.

We claim:

1. The combination in an ironing machine, of a rotatable ironing roll, a relatively movable shoe extending substantially throughout the length of said roll, means for actuating said roll, and means for swinging said shoe toward said roll in a horizontal plane containing the axis of rotation of said roll.

2. The combination in an ironing machine, of a horizontal rotatable ironing roll, an ironing shoe, means for rotating said roll, a lever having a resilient part supporting said shoe and having a pivotal axis extending vertically, and means for actuating said lever to move said shoe toward and from said roll.

3. The combination in an ironing machine, of an ironing roll rotatable about a horizontal axis, an ironing shoe, means for rotating said roll, a lever supporting said shoe and pivoted to move above a vertical axis, and means for actuating said lever to move said shoe toward and from said roll.

4. The combination in an ironing machine, of a rotatable ironing roll, an ironing shoe, means for rotating said roll, a single lever pivotally supported adjacent one end of said roll and having a resilient part at one end thereof connected to said shoe, said lever extending substantially parallel to said roll, and power actuated means connected to the other end of said lever for moving it about its pivot to effect relative movement of said shoe with respect to said roll.

5. The combination in an ironing machine, of an ironing roll rotatable about a horizontal axis, an ironing shoe, means for rotating said roll, a lever pivotally supported adjacent one end of said roll to move about a vertical axis, means for connecting one end of said lever to said shoe whereby said shoe is supported on said lever, and means connected to the other end of said lever for actuating said lever to move said shoe toward and from said roll.

6. The combination in an ironing machine, of an ironing roll rotatable about a horizontal axis, an ironing shoe, means for rotating said roll, a lever pivotally supported adjacent one end of said roll and having a resilient arm extending on the rear side of said shoe, means for connecting said resilient arm to said shoe, and operating mechanism connected to the other end of said lever for actuating said lever to move said shoe toward and from said roll.

7. The combination in an ironing machine, of a rotatable ironing roll, an ironing shoe, means for rotating said roll, a lever pivoted at an intermediate point and having a resilient arm extending lengthwise of and connected to said shoe.

and means connected to the other end of said lever for effecting movement of said shoe toward and from said roll.

8. The combination in an ironing machine, of 5 a rotatable ironing roll, an ironing shoe, means for rotating said roll, a single lever pivoted at an intermediate point and having an arm extending lengthwise of and connected to and supporting said shoe, and means comprising an eccentric 10 connected to the other end of said lever for effecting movement of said shoe with respect to said roll.

9. The combination in an ironing machine, 15 of a housing, an ironing roll supported by and extending longitudinally from said housing, a lever pivotally supported on said housing and extending alongside said roll, a shoe supported by said lever for cooperation with said roll, and driving mechanism located in said housing for rotating said roll and for oscillating said lever about 20 its pivot to move said shoe toward and from said roll.

10. The combination in an ironing machine, 25 of a housing, an ironing roll supported by and extending longitudinally from said housing, a lever pivotally supported on said housing with one end located in said housing and the other end projecting therefrom, an ironing shoe supported by the projecting end of said lever, an eccentric 30 located in said housing and connected to said first named end of said lever, and driving mechanism located in said housing for rotating said roll and actuating said eccentric.

11. The combination in an ironing machine, 35 of a housing, an ironing roll supported by and extending longitudinally from said housing, a lever pivotally supported on said housing with one end located in said housing and the other end pro-

jecting therefrom, an ironing shoe supported by the projecting end of said lever, an eccentric located in said housing and connected to said first named end of said lever, driving mechanism located in said housing for rotating said roll and 80 actuating said eccentric, and means for holding said eccentric in any one of a plurality of positions.

12. The combination in an ironing machine, 85 of a housing, an ironing roll supported by said housing and projecting longitudinally therefrom, driving mechanism in said housing for rotating said roll, an eccentric adapted to be actuated by said driving mechanism, a lever pivotally supported at an intermediate point on said housing with one end thereof connected to said eccentric, 90 an ironing shoe supported by the other end of said lever for cooperation with said roll, and means for establishing a driving connection between said eccentric and said driving mechanism. 95

13. The combination in an ironing machine, 100 of a housing, an ironing roll supported by said housing and projecting longitudinally therefrom, driving mechanism in said housing for rotating said roll, an eccentric adapted to be actuated by said driving mechanism, a lever pivotally supported at an intermediate point on said housing with one end thereof connected to said eccentric, 105 an ironing shoe supported by the other end of said lever for cooperation with said roll, means including a clutch for establishing a driving connection between said mechanism and said eccentric, and means for automatically disengaging said clutch and holding said eccentric against rotation when said shoe is in either of two extreme positions. 110
